UNITED STATES PATENT OFFICE

JOHN RECTOR PETERS, OF NEW YORK, N. Y., ASSIGNOR OF ONE-TENTH TO JOHN J. PLANETA, OF NEW YORK, N. Y.

SNOW MELTING APPARATUS

Application filed September 26, 1929. Serial No. 395,354.

This invention relates to an improved machine for removing snow from streets or car tracks, it being understood that it may also be used for removing grass and weeds if so desired.

One object of the invention is to provide a machine which is so constructed that flames from a burner may be directed downwardly toward the snow, and further to hold the burner in a supporting frame which is suspended beneath a vehicle body or other suitable carrier which in addition to carrying the burner, also carries a box like structure which serves as a container for compressed air which may be directed downwardly towards the burner.

Another object of the invention is to so construct this machine that the compressed air box may serve not only as a container for the compressed air but may also serve as a deflector plate which will serve to throw the heat of the burner downwardly, the compressed air serving to downwardly blow steam which might have a tendency to rise and smother the flame of the burner and in addition to this function, also serving to supply oxygen to assist in providing a good flame.

Another object of the invention is to so construct the machine that the supporting frame which carries the burner and compressed air box may be tilted vertically out of a horizontal position and thus easily brought into position above snow formed into irregular drifts.

This invention is illustrated in the accompanying drawings, wherein:

Figure 1 is a view showing the improved machine partially in side elevation and partially in longitudinal section.

Figure 2 is a plan view of the burner and the supporting frame which carries the same.

Figures 3, 4 and 5 are sectional views taken along the lines 3—3, 4—4 and 5—5 respectively of Fig. 2.

Figure 6 is a fragmentary sectional view through one end portion of the burner pipe and water jacket pipe.

This machine is provided with a carriage

1 and will be provided with a platform 2 and a conventional frame construction. In the present illustration, this carriage is a horse-drawn vehicle, but it is to be understood that the invention is not limited to the specific 55 form of carriage disclosed.

Upon the platform 2 there has been mounted a steam boiler 3, a water tank 4, a fuel tank 5, and turbine motors 6, 7 and 8 which receive their steam supply from the boiler 3 through the conductor pipe 9. The motor 6 operates a water pump 10 which is of a conventional construction and the motors 7 and 8 operate air compressors 11 and 12 which are also of a conventional construction. 60 Windlasses 13 are carried by the platform 2 and carry chains 14 or other suitable flexible cable elements which extend through openings in the platform and carry hooks 15 at their free ends. 65

The frame 16 which is to carry the burner and compressed air box, is in the form of an open substantially rectangular frame formed of angle iron and having side and end bars. This frame is positioned beneath the carriage 70 intermediate its length as shown in Fig. 1 and is suspended from the carriage by means of hanger bars 17 which are secured at their upper ends to the carriage and have their lower ends loosely connected with the side bars of the frame 16 by means of fasteners 18 which serve as pivot pins to pivotally mount the frame and thus permit of its being held in a horizontal position as shown in full lines in Fig. 1 or tilted to an inclined position as indicated by dotted lines in this figure. The end bars of the frame are connected with the hooks or engaging elements 15 of the chains 80 by bolts 19 and it will be seen that when it is desired to tilt the frame, it is simply necessary to operate the two windlasses so that one of the chains will be wound upon the windlass and the other chain let out.

The burner is supported on the frame 16 and rests upon the inwardly extending flanges of the angle iron bars from which the frame is formed. This burner embodies an inner pipe 20 and an outer pipe 21, the inner pipe 20 being termed the burner pipe and the outer pipe 21 being termed a water jacket 95 jacket pipe.

pipe. The burner is formed of horizontally elongated portions or sections 21' which extend substantially parallel to each other as shown in Fig. 2 and have their end portions connected by elbows 21''. It will be noted that the elbows 21'' rest upon the inwardly extending flanges of the side bars of the frame 16 and that therefore the burner has its portions or sections 21' extending across the frame and supported by the side bars of said frame. Each end of the burner pipe 20 will be closed by means of a plug 22 as shown in Fig. 6 and the sections of the burner and water jacket pipes will be provided with alined threaded openings so that the nozzles 23 may be passed through these alined openings. By providing this construction which is shown clearly in Figs. 3 and 4, the nozzles 23 serve not only as nozzles, but also as means for centering the burner pipe within the water jacket pipe. The nozzles of one section of the burner are positioned in staggered relation to the nozzles of adjoining sections and therefore the jets of flame will be well distributed and the snow will be quickly melted when the machine is in use. Each end of the water jacket pipe will be provided with a coupling 24 so that the ends of the water jacket may be connected with flexible pipes 25 which lead from pipes 26 and 27. The pipe 26 leads from the water tank 4 and the pipe 27 leads from the pump 10. This pump 10 is connected with the water tank by means of a pipe 28 and it will be readily seen that when the pump is in operation, the water will be circulated through the water jacket and the burner pipe will be kept sufficiently cool to prevent danger of explosion from over-heating. The fuel is carried in the tank 5 which is connected with the air compressor 11 by means of a pipe 29 and is provided with a conduit pipe 30 which is connected with the manifold 31 by means of a flexible pipe section 32. This manifold 31 is provided with outlets in which will be screwed nipples 33, the nipples 33 being passed through registering threaded openings in the couplings at one side of the burner. Therefore, the fuel may be fed into the sections of the burner and the burner kept properly filled with the fuel. Each section of the burner is provided with a valve 34 which is constructed as shown in Fig. 4. By properly adjusting the valves the fuel may be permitted to enter certain sections of the burner and excluded from other sections if desired. It will thus be seen that when the burner is first lighted the fuel may be admitted to the section at one end of the burner and after this section has been lighted, the other sections successively brought into operation. The sections will thus be well heated before lighted and the device will operate in a very efficient manner.

As previously explained, it is desired to have the heat directed downwardly toward

the snow which is to be melted and therefore there has been provided a box 35 which rests in the supporting frame 16 above and preferably upon the burner. This box which will be termed the compressed air box is provided with an inlet which is connected with the pipe 36 of the air compressor 12 by a length of flexible piping 37. Outlet nozzles, 38, are screwed into openings formed in the bottom of the box 35 and are positioned adjacent the sections of the burner as shown in Fig. 3. From an inspection of this figure it will be readily seen that the air from the box will pass through these nozzles 38 and will be directed downwardly so that this air will serve to mix with the gas which passes off through the nozzles 23, thus providing a very good combustible fluid. These jets of air will also serve to dissipate steam formed by the melted snow and there will be no danger of the steam forming a blanket which would tend to smother the flame.

When this machine is in use, it is moved along and the flame directed against the snow thus melting it. If it is found that the snow has been formed into drifts or piles over which the frame cannot be readily moved when in a horizontal position, the frame will be tilted as indicated by dotted lines in Fig. 1 and the machine can then be easily moved into the proper position above the snow. If it is not desired to make use of all of the burner sections, the valves of any desired number may be closed and the fuel will be prevented from entering these sections. It will of course be obvious that the pipes leading to the various turbine motors can be provided with suitable valves so that certain of these motors can be cut off without the remaining ones being affected.

I claim:

1. A machine of the character described comprising a carriage, a support mounted beneath the carriage for vertical tilting movement, means carried by said carriage for pivotally adjusting said support, a burner carried by said support for directing flame downwardly, and a compressed air box carried by the support above the burner and having outlets for directing air adjacent the flame of the burner.

2. A snow melting machine comprising a carriage, a rectangular substantially horizontal frame mounted on said carriage and embodying parallel side bars each formed of angle metal and provided with one vertically projecting flange and one inwardly projecting horizontal flange, a burner embodying a plurality of elongated burner pipes extending between said side bars, the ends of said burner pipes resting on said inwardly projecting horizontal flanges and abutting said vertical flanges, said burner pipes having means for directing jets of flame downwardly, a substantially flat compressed-air

box resting upon said burner pipes and substantially coextensive in area with the zone occupied by said burner pipes, said box being provided with means for downwardly directing jets of air adjacent said burner pipes, fuel supply means for the burner mounted on said carriage, and compressed air supply means for said box also mounted on said carriage.

10 3. A snow melting machine comprising a carriage, a rectangular substantially horizontal frame mounted on said carriage and embodying parallel side bars, a burner embodying a plurality of elongated burner pipes 15 extending between and supported by said side bars, said burner pipes having means for directing jets of flame downwardly, a substantially flat compressed-air box disposed immediately over said burner pipes and substantially co-extensive in area with the zone 20 occupied by said burner pipes, said box being provided with means for downwardly directing jets of air adjacent said burner pipes, fuel supply means for the burner mounted 25 on said carriage, and compressed air supply means for said box also mounted on said carriage.

4. A machine of the character described comprising a carriage, a support beneath said carriage, suspending means pivotally connected with said support intermediate the length of the latter, said suspending means being carried by said carriage, means for pivotally adjusting said support and retaining 30 it in adjusted position, a burner carried by said support, a compressed-air box carried by said support above said burner for deflecting flame downwardly from the burner, said box having outlet nozzles for directing jets of air 35 downwardly, and means carried by said carriage for supplying air under pressure to said box.

In testimony whereof I have hereunto affixed my signature.

45 JOHN RECTOR PETERS.
